MEANS FOR MEASURING MOISTURE CONTENT OF FIBROUS MATERIALS

Earl J. Haverstick, Oakmont, Pa., assignor to Westinghouse Electric & Manufacturing Company, a corporation of Pennsylvania

Application May 31, 1930, Serial No. 458,560

4 Claims. (Cl. 73—51)

My invention relates to indicators and it has particular relation to indicators used to determine the moisture content of paper or any other fibrous material.

5 All devices of this character made according to the teachings of the prior art, and with which I am familiar, have had the disadvantages of being somewhat complicated and expensive.

It is, accordingly, an object of my invention 10 to provide an entirely new, simple and inexpensive means for determining the moisture content of a fibrous material, such as paper.

15 Although the present invention relates to the indication of the moisture content of a fibrous material, it is to be noted that the indicator can be utilized as a controlling device to regulate the amount of heat applied to fibrous material to be dried thereby.

According to my invention, I make use of the 20 fact that the coefficient of friction between a moving web of fibrous material and a piece of solid material in frictional engagement with and dragging thereon is a measure of the moisture content of the fibrous material, within certain 25 limits. In my experiments with a moving web of paper and a small block of smooth glass, I have found that the moisture content of paper is substantially directly proportional to the coefficient of friction between the glass and moving 30 paper when the moisture is within the limits of 4% and 10%, and sufficiently so for other values of moisture content above and below these 35 values. This principle can, therefore, be used in practical applications since most types of paper have in their final form, a moisture content within the percentage limits mentioned.

The novel features that I consider characteristic of my invention are set forth with particularity in the appended claims. The invention, 40 however, both as to its organization and its method of operation, together with additional objects and advantages thereof, will best be understood from the following description of a specific embodiment, when read in connection with the accompanying drawing, in which:

Figure 1 is a curve showing the relation between the coefficient of friction of a piece of glass on a moving web of paper and the moisture content of the paper with which the glass is in frictional 45 engagement.

Fig. 2 is a diagrammatic side view of the dryer of a paper machine provided with my improved moisture indicator.

Fig. 3 is a plan view of the dryer and the 50 improved indicator, and

Fig. 4 is a perspective view of a block of solid material and a securing means, constituting a part of my indicator.

The present embodiment of the invention is 5 shown in connection with a dryer of usual construction, including a plurality of heated hollow drums or cylinders 1, about which the paper web passes in a well known manner. The cylinders are heated by steam in the usual manner, the steam being supplied from a manifold 2, which is 10 connected to the respective cylinders at their axes, thereby not interfering with the rotation of the cylinders. Suitable means (not shown) are provided to drive the hollow cylinders 1. The steam leaves the manifold 2 through pipe 15 sections 3, and flows through the rolls 1 into another header 4, and either out into the open air or into a condensing system, as may be desired.

The plurality of dryer drums 1 are supported 20 in suitable bearings (not shown in detail) in a pair of frames 5.

The wet end of the paper machine is not shown 25 as any usual or desired type may be used, and while I have illustrated and described a specific embodiment of a dryer mechanism, it is to be understood that I do not desire to be limited thereto as the device and method embodying my invention hereinafter to be described may be utilized with any machine making units of fibrous 30 material or with any paper making and paper drying machine.

I have illustrated a set of calendar rolls 6 rotatably mounted in a frame 7 and a reel structure 8 on which the web of dried paper 9 may be 35 finally wound.

It is highly desirable if not actually necessary to check the moisture content of the web of fibrous material and I provide a pair of bracket arms 11, one end of each of which is secured to the end members of the calendar frame 7 and extending toward the dryer rolls. A rod or shaft 12 extends between the bracket arms 11, the ends of the rod or shaft 12 being rigidly mounted on the arms. A screw threaded shaft 13 spaced 40 from the rod 12 has its ends rotatably supported in the bracket arms 11 and a crank arm 14 is secured to one end of the shaft to permit of turning the same.

The rod 12 and the shaft 13 extend parallel to 45 each other and support a carriage 16, having two openings extending laterally therethrough to receive the rod 12 and the screw threaded shaft 13, whereby the carriage is supported above the moving web of paper 9 in such manner as to be mov- 50 55

able laterally thereof by turning the crank 14 to effect a turning movement of the shaft 13 extending through one of the two openings in the carriage 16. The opening in carriage 16 through which shaft 13 extends has internal screw threads to cooperate with those on the shaft 13.

5 A block 17 of solid material, which may be of glass, or preferably of wood, and which may be four inches wide by six inches long and one-half 10 inch or so thick, is placed on the upper surface of the web 9 in frictional engagement therewith and is yieldingly restrained from movement with the web by a cord 18 which has one end thereof attached thereto at its rear edge portion. The 15 cord 18 passes over two pulleys 19 mounted in spaced relation at the rear portion of the carriage and its other end is secured to a pulley 21 mounted on a shaft 22 of an indicating instrument 23. The shaft 22 is yieldingly restrained from turning 20 by suitable biasing means, such as a spring (not shown). A pointer 24 is secured to the shaft 22 and cooperates with a suitable scale whose indicia may indicate either values of the coefficient of friction or more directly the percentage of 25 moisture content.

As has already been set forth, I have found 30 that there is a direct relation between the moisture content of a flat piece of fibrous material and the friction between it and a block of solid material in frictional engagement therewith when there 35 is relative motion therebetween, and the mechanical structure hereinbefore set forth permits of determining in a very simple and easy manner the drag and, therefore, the friction between a block of solid material and a flat sheet of fibrous material upon relative movement therebetween.

The screw threaded shaft 13 may be rotated by 40 its crank arm 14 to laterally shift the position of the carriage 16 to obtain any desired location of the block 17 on the web 9. If it should be found that there is a variation in the moisture content across the web of material, the carriage and the solid block of material may be moved laterally of the web of fibrous material to obtain 45 readings on selected portions of the web or to obtain a number of readings which may be averaged.

I have found that a block of wood will give ex-

cellent results when utilized as the friction member, the indications being constant over long periods of use of such a block of wood and the block itself being worn to a very small degree by its frictional engagement with the moving sheet of fibrous material.

5 I do not wish to be restricted to the particular details illustrated and described, as various modifications thereof may be effected without departing from the spirit and scope of my invention. I 10 desire, therefore, that only such limitations shall be imposed as are indicated in the appended claims.

I claim as my invention:

1. Means for determining the moisture content of a moving sheet of fibrous material including a block reposing freely in contact with the moving sheet, means for yieldingly holding the block of material against movement, and an indicator arm actuated by the holding means for 20 indicating the drag on the block of solid material produced by the moving sheet.

2. In combination, a member presenting a surface to be disposed in frictional contact with a continuously moving web of paper, a biased indicator arm, means for securing said member to said indicator arm, and a scale associated with said indicator arm calibrated in terms of percent moisture.

3. In combination, a block to be disposed on 30 the upper surface of a horizontally moving web of fibrous material, a biased indicator arm, and means interconnected between the block and the indicator arm whereby the block is anchored from movement with the web and the indicator 35 arm is deflected in accordance with the drag exerted on the block by the web.

4. Apparatus for determining the moisture content of a moving web of material, comprising 40 a member adapted to be placed in contact with the moving material, measuring means connected to said member to be actuated by the frictional drag on said member caused by relative movement between said member and material, said measuring means including an indicator calibrated in direct terms of moisture content of 45 the material.

EARL J. HAVERSTICK.
